His Attorney.

UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

Application filed July 20, 1923. Serial No. 652,853.

To all whom it may concern:

Be it known that I, OSCAR JUNGGREN, a citizen of the United States, residing at Schenectady, county of Schenectady, State 5 of New York, have invented certain new and useful Improvements in Elastic-Fluid Turbines, of which the following is a specification.

The present invention relates to elastic-10 fluid turbines and especially elastic-fluid turbines intended for operation with pressures higher than those now in common use. To obtain better efficiencies in elastic-fluid turbines, the use of elastic fluid of higher and 15 higher pressures is being resorted to and this makes increasingly difficult the problem of providing a structure sufficiently strong to confine the elastic fluid without resorting to unduly heavy parts, and sufficiently tight to 20 prevent leakage. This is particularly true at the high pressure or admission end of the turbine where the casing is subjected to the highest pressure and also the highest temperature.

25 The object of my invention is to provide an improved structure which, while being comparatively light in weight, is at the same time amply strong to safely confine the high pressure elastic fluid, and also to provide 30 a structure which is fluid-tight and will remain so under all conditions of operation.

For a consideration of what I believe to 35 be novel and my invention, attention is directed to the accompanying description and the claim appended thereto.

In the drawing, Fig. 1 is a vertical, sectional view of a structure embodying my invention, and Fig. 2 is a sectional view taken 40 on line 2—2, Fig. 1, and drawn to a smaller scale.

Referring to the drawing, 5 indicates the shaft of an elastic-fluid turbine, 6 the surrounding casing or shell, 7 the admission conduit which conveys elastic fluid to an annular chamber or chest 7^a, and 8 the exhaust conduit. In Fig. 1 only the admission end of the turbine is illustrated. The end wall at the high pressure end of the turbine casing is indicated at 9 and is formed integral 45 with surrounding casing or shell 6. Mounted on shaft 5 are the turbine bucket wheels 10, and carried by casing 6 are the diaphragms 11 which divide the turbine into stages. Only the first of the high pressure 50 stages are shown in Fig. 1 of the drawing

but it will be understood that the turbine may comprise any suitable number of stages. The casing is split horizontally as indicated at 12, this being the usual arrangement used to make assembling and dismantling 60 convenient.

Now, according to my invention, I provide a solid annular ring structure 13 which surrounds shaft 5 and serves to tie or anchor end wall 9 to the surrounding casing wall 6, 65 at the same time serving with end wall 9 to define the annular elastic-fluid chamber 7^a. The end wall 9 is subjected to the pressure of the high pressure elastic fluid in chamber 7^a so there is a large force tending to push it 70 outwardly and since it is split horizontally it is much less able to withstand this pressure than would be the case were it a solid annular ring. It follows, therefore, that with prior structures it would be necessary 75 to make the head exceedingly heavy if it were required to withstand high pressure, a thing to be avoided not only because of the additional weight but also because an extremely heavy wall means high heat stresses 80 as the wall expands and contracts with changes in temperature. By the use of a tie ring or anchoring ring which connects the head to the main turbine shell, strength and support is given to end wall 9 so it need 85 not be made extremely heavy in order to hold the pressure to which it is subjected. The structure 13 being in the form of a solid ring has great strength and is able to lend support to end wall 9 without itself being 90 unduly heavy.

Ring structure 13 is shown in Figs. 1 and 2 as comprising a plate portion 14 having a rim 15 which fits in a groove 16 in the two halves of casing 6, and a cylindrical portion 95 17 which extends axially along the shaft and has a rim 18 which fits in a groove 19 in the edge of the central opening in end wall 9. The elastic-fluid pressure in chamber 7^a serves to hold the annular, radially-extending, 100 engaging surfaces A and B of rims 15 and 18 in close contact with the walls of grooves 16 and 19 so that leakage is prevented. The axially-extending surfaces C, D and E are spaced apart to permit of radial 105 expansion of ring structure 13 relatively to the turbine casing. Bolted to plate portion 14 is a nozzle ring 20 for directing elastic fluid to the buckets of the first stage wheel 10 and in plate 15 are suitable passages 21 110

through which the elastic fluid flows to the nozzles.

Between ring structure 13 and the shaft 5 there is arranged a suitable packing 22 5 to prevent leakage of elastic fluid, the stationary portion of the packing being fastened to structure 13 as indicated at 23. Any suitable form or arrangement of packing may be used as found desirable, the one 10 illustrated being a packing of the nature of that disclosed and claimed in my co-pending application Serial No. 627,921, filed March 23, 1923.

In assembling the turbine, ring structure 15 13 is placed over the shaft before the rotor is lowered into the lower half of the turbine shell. When the rotor is then placed in the lower half of the shell, rims 15 and 18 are guided into grooves 16 and 19 so that 20 the ring structure will be supported in vertical position. The ring is centered by the annular surface F. The upper half of the turbine casing is then put into place in the usual manner, the portions of grooves 16 25 and 19 in it taking over rims 15 and 18. As will be clear, ring 13 does not interfere with the assembly or dismantling of the machine or with removal of the upper half of the casing for inspection purposes. As is well 30 understood, the diaphragms 11 are usually split horizontally and the upper halves are fixed in the upper half of the turbine casing.

My invention, while it is of particular 35 utility in connection with turbines intended for operation at high pressures, for example, pressures of the order of 300 lbs. and higher,

is by no means limited to use in such turbines. It may be with advantage used in connection with turbines operated with 40 elastic fluid of the pressures now in ordinary use.

In accordance with the provisions of the patent statutes, I have described the principle of operation of my invention, together 45 with the apparatus which I now consider to represent the best embodiment thereof; but I desire to have it understood that the apparatus shown is only illustrative, and that the invention may be carried out by other 50 means.

What I claim as new and desire to secure by Letters Patent of the United States, is,—

The combination in an elastic-fluid turbine, of a rotor having a shaft, a surrounding split casing, an end wall formed integral with the casing, said end wall having an opening through which the shaft projects, a solid ring structure having an axially-extending hub which surrounds the shaft in 55 spaced relation thereto, said ring structure serving to anchor the end wall to the surrounding casing, and defining with the end wall an elastic-fluid chamber, a packing structure attached to and carried by the hub 60 in the spaces between it and the shaft, whereby said packing structure moves radially 65 with the ring structure when the ring structure expands and contracts, and nozzle means carried by said ring structure. 70

In witness whereof, I have hereunto set my hand this 19th day of July, 1923.

OSCAR JUNGGREN.
